(57) **CLAIM**

The ornamental design for shank piece for a bridle bit, as shown and described.

DESCRIPTION

FIG. 1 is a front view of a shank piece for a bridle bit showing my new design;

FIG. 2 is a cross-sectional view thereof taken along line 2—2 of FIG. 1;

FIG. 3 is a front view of a second embodiment of a shank piece for a bridle bit showing my new design;

FIG. 4 is a cross-sectional view thereof taken along line 4—4 of FIG. 3; and,

FIG. 5 is a front view of a third embodiment of a shank piece for a bridle bit showing my new design, it being understood that the appearance from the rear forms no part of the claimed design.

The broken lines shown in newly amended FIGS. 1, 3, and 5 are for illustrative purposes only and form no part of the claimed design.
